WINDOW REGULATOR MECHANISM

Waldo L. Kraemer, Brooklyn, N. Y., assignor to
Kearfott Engineering Company, Inc., a cor-
poration of New York

Application December 22, 1932, Serial No. 648,359

2 Claims. (Cl. 268—130)

In window constructions utilized in traveling vehicles such as automobiles and ships, for example, the windows are commonly operated by regulator mechanism which transforms rotary motion of a crank or handle into closing and opening movement of the window. Many types of regulating mechanisms have been devised for these windows but such regulating mechanisms as have heretofore been used lack one or more of the features which are desirable in a window regulator. These desirable features include a positive acting mechanism, a large mechanical advantage, as the window panes used in the windows of ships often weigh as much as three hundred pounds, a low efficiency to avoid overhauling and insure that the window pane will remain in the position it is left by the operator, a high speed ratio between the operating handle and the window pane so that the window pane may be quickly raised and lowered, and a construction which is comparatively simple and inexpensive.

A regulator mechanism which is used extensively in windows built for ships, for example, and which is satisfactory in respect to many of the desirable features, is that shown in my prior Patent No. 1,695,691 granted December 18, 1928 and in which there is provided a screw shaft with a helical thread. This screw shaft is supported in a thrust bearing in the waist rail of the window frame and depends therefrom to the lower cross member of the window frame. On the shaft, there is a nut which is connected to the lower edge of the window-pane. A handle outside of the window frame is connected through gears and shafts to the threaded shaft. Rotation of the handle is thus transformed into rotation of the screw shaft and since the nut on the shaft is restrained from rotational movement it travels longitudinally of the shaft, moving the window-pane in the window-pane guideways. Such a regulator has a low speed ratio between the window-pane and the operating handle, and the necessity for accurate alignment of the screw shaft with respect to the side members of the window frame renders the construction somewhat difficult and expensive.

By my present invention, I am enabled to construct a positive acting window regulator mechanism for windows of the type mentioned, which embodies all of the above mentioned desirable features, namely, a high mechanical advantage, an efficiency such that there is no overhauling, simplicity of construction and a high speed ratio between the operating handle and the window-pane. In accordance with my invention, I con-

struct a regulator mechanism by utilizing differential circular drive members in conjunction with a flexible motion transmitting member. The differential drive members and the flexible motion transmitting member are in operative engagement so that rotation of the drive members is transformed into motion of the flexible motion transmitting member. This latter member is connected to the window-pane and actuates the window-pane in the window-pane guideways. 10 The differential drive members provide a mechanical advantage such that the heaviest of window-panes are readily and easily moved in the guideways and the efficiency is such that there is no overhauling. The flexibility of the motion 15 transmitting member which connects the drive members to the window-pane eliminates any necessity for a delicacy or accuracy of alignment in the regulator mechanism and thus provides a construction which is comparatively inexpensive 20 to manufacture; the proportions of the members provide a high speed ratio; and the arrangement constitutes a positive acting mechanism.

Specifically, a regulator constructed in accordance with my invention is adapted for use in 25 conjunction with a window construction including a window frame, window-pane guideways and a window-pane mounted in the window-pane guideways. The window regulating mechanism includes a waist rail which is mounted transversely of the window frame at approximately the longitudinal center thereof. This waist rail is provided at the center thereof with a housing in which there is journaled a shaft, transverse to the plane of the window frame. On the shaft, 30 a sprocket is mounted and secured to the shaft for rotation therewith. A second sprocket of slightly different diameter is also mounted on the shaft for rotation with respect to the shaft. To this second sprocket there is secured an annular 35 gear which through an idler pinion meshes with a spur gear secured to the shafts. A manually operative crank handle is provided for rotating the shaft from the outside of the frame and upon rotation of the shaft, one of the sprockets rotates with the shaft and the other rotates in a 40 direction relatively reversed to the direction of rotation of the shaft. Over the upper portion of these sprockets there is draped an endless chain, the chain being suspended on each side of the 45 longitudinal axes of the sprockets and forming two loops. In one of these loops, there is an idler sprocket engaging the chain. This idler sprocket is mounted in a saddle which is secured to a 50 bracket that is connected to the lower edge of the 55

window-pane. An idler pulley mounted in a saddle engages the other loop in the endless chain. On the lower cross member of the frame there is mounted, in a stationary bracket, another idler pulley. A flexible member, such as a piece of chain, is connected between the bracket on which the idler sprocket is mounted and saddle carrying the idler pulley engaging a loop in the endless chain. This flexible member also engages the pulley secured to the lower cross member of the frame and thus tensions the endless chain. As the drive sprockets are rotated, the loops formed by the endless chain move longitudinally of the frame member, that is, towards and away from the drive sprockets. The differential arrangement of the sprockets provides a large mechanical advantage. Through the connection to the window-pane, movement of the endless chain in this manner is transformed into movement of the window-pane in the guideways. The efficiency of the transmitting or regulating mechanism is such that the window-pane will not overhaul and the speed ratio between the drive sprockets and the window-pane is comparatively high.

A more clear understanding of my invention will be had from the following particular description of one embodiment thereof which is shown in the accompanying drawing in which:

Fig. 1 is a front elevation of a window including a regulator of my invention;

Fig. 2 is a side, sectional elevation of the same taken on the line 2—2 of Fig. 1;

Fig. 3 is an enlarged, fragmentary, sectional elevation through the waist rail;

Fig. 4 is an enlarged, fragmentary, sectional plan taken on the line 4—4 of Fig. 3; and

Fig. 5 is an enlarged, fragmentary, sectional end elevation taken on the line 5—5 of Fig. 1.

The window construction illustrated in the drawing is one that is particularly suitable for a ship. It is, however, understood that the particular application of the window on which the regulating mechanism is used is quite immaterial, the type of window construction illustrated being chosen for its simplicity. In the window construction illustrated, there is a frame having an upper cross member 1a, side members 1b and 1c, and a lower cross member 1d. The frame members are angular in cross section, the frame having an outwardly extending circumambient flange 2 which is utilized for bolting the window frame to the side of a ship. The window frame is substantially twice as long as the window opening therethrough which opening is defined by the upper cross piece 1a of the frame member, a portion of each of the two sides 1b and 1c thereof and a waist rail 3 which is mounted at substantially the longitudinal center of the window frame.

The particular waist rail illustrated is of a special construction as it includes a housing 4 at the transverse center thereof. This housing is cast integral with the waist rail and is provided with a removable cover plate 5. The rear wall of the housing and the cover plate are bored to form a journal for a shaft 6. The shaft has a hollow squared forward end which is adapted to receive the squared end of an operating crank handle 7 for manually rotating the shaft. Adjacent its front end, the shaft is provided with a flange 6a to which a sprocket 8 is secured by means of machine screws 9. Immediately behind this sprocket there is mounted another sprocket 10 which is spaced from the first sprocket by

an elongated hub 10a. This second sprocket is rotatably mounted upon the shaft for rotation with respect to the shaft. An annular gear 11 is secured to the sprocket 10 and engages an idler pinion 12 which is rotatably mounted upon a stub shaft 13 supported in the rear wall of the housing. The idler pinion 12 meshes with a spur gear 14 secured on the shaft 6 for rotation therewith. With this construction, it will be apparent that when the shaft 6 is rotated manually through the crank handle, one of the sprockets 8 is rotated with the shaft and the other sprocket 10 is rotated in a direction relatively reversed to the direction of rotation of the shaft. The two sprockets are slightly different in diameter and form a pair of differential drive members.

Engaging each of the differential drive members or sprockets there is an endless flexible chain 15. The chain is draped over the upper half of the two sprockets so that there are two suspended ends, one on either side of the longitudinal axes of the sprockets and each end forming a loop. In one of these loops there is an idler sprocket 16 engaging the endless chain. The idler sprocket is mounted in a bifurcated bracket or saddle 17 having a round extension or stud 17a thereon. The saddle is connected to a bracket 18 through the extension 17a, the free end of which is threaded and extends through an opening in a lateral flange 18a formed on a bracket 18. The stud extending from the saddle is rotatably mounted in the bracket 18 so that it may rotate about an axis perpendicular to the axis of the idler sprocket. To this bracket 18 there is also secured a clamp 19 which receives and firmly grips the lower edge of the window-pane 20. In the other loop formed by the endless chain, there is an idler pulley 21 which is also mounted in a bifurcated bracket or saddle 22.

The two saddles 17 and 22 are connected together by a flexible chain 23, the ends of which are connected one to each of the saddles. This latter chain engages, intermediate its ends, an idler pulley 24 which is rotatably mounted between the arms of a bifurcated bracket 25 secured to the lower cross member 1d of the window frame. With this construction the endless chain 15 is maintained under slight tension and upward movement of one side of the chain is transmitted as a downward force on the other side of the chain so that the chain is at all times held under slight tension and there can not be any slack, the looped ends of the chain following a definite path of operation.

From the above description of the regulator mechanism illustrated it will be apparent that as the shaft 6, on which the drive sprockets 8 and 10 are mounted, is rotated to the left, as shown in Fig. 1, for example, the amount of chain 15 on the left of the sprockets will be gradually lessened in accordance with the difference of the circumference of two sprockets and will be transferred to the right side of the axis of the sprockets. The transfer will of course be equal so that the idler pulley 21 will move downwardly and the idler sprocket 16 will move upwardly, drawing the bracket 18 with it and consequently moving the window-pane upwardly. Rotation in the opposite direction will cause downward movement of the idler pulley, or rather upward movement of the idler pulley which through the flexible connecting chain 23 will draw the idler sprocket downwardly and consequently open the window. It is to be noted that by virtue of this connecting chain 23, the idler sprocket and bracket 18

is connected to the drive sprockets through positive acting mechanisms.

The mechanical advantage resulting from this differential drive is such that a three hundred 5 pound window-pane is readily and easily moved in the window-pane guideways. The efficiency, however, is such that the window-pane will remain in any position in which it is left. The regulator is positive in its action which is necessary 10 in case of the window-pane becoming stuck in the closed or any other position. The speed ratio between the crank handle 7 and the bracket 18 is comparatively high so that the window-pane may be rapidly opened and closed.

15 It is obvious that various changes may be made by those skilled in the art in the details of the embodiment shown in the drawing and described immediately above within the principle and scope 20 of my invention as expressed in the appended claims.

I claim:

1. In a window construction having a frame and a window-pane slidably mounted in the frame, a regulator for the window-pane comprising 25 a waist rail mounted at substantially the longitudinal center of the frame, a pair of differential circular drive members rotatably mounted on the waist rail, an endless flexible motion-transmitting member engaging the drive members on the upper side thereof and forming two depending loops, an idler engaging the motion-transmitting member at each of said loops, another 30 idler rotatably mounted on the lower cross mem-

ber of the frame, a tension member connected between the idlers engaging the motion-transmitting member and engaging the idler mounted on the lower cross member, a connector for connecting the motion-transmitting member to the window-pane, and means for rotating the drive members to move the window-pane.

2. In a window construction having a frame and a window-pane slidably mounted in the frame, a regulator for the window-pane comprising 10 a waist rail mounted at substantially the longitudinal center of the frame, a shaft rotatably supported by the waist rail, a sprocket secured to the shaft, another sprocket rotatably mounted on the shaft and connected thereto for rotation in relatively reverse direction to the movement of the shaft, the two sprockets forming a pair of differential drive wheels, an endless chain engaging the sprockets on the upper side thereof and forming two depending loops, one on 15 each side of the axis of the shaft, an idler sprocket engaging the chain in one of said loops, an idler pulley engaging the chain in the other of said loops, a pulley rotatably mounted on the lower cross member of the frame, a flexible member secured to said idler sprocket and pulley and engaging the pulley mounted on the cross member of the frame, a connector for connecting the motion-transmitting member to the window-pane, and means for rotating the shaft mounted on the 20 waist rail to move the window-pane.

WALDO L. KRAEMER.
